UNITED STATES PATENT OFFICE.

RODNEY J. WOOD, OF DAYTON, OHIO.

FILING CABINET.

Application filed February 15, 1924. Serial No. 693,057.

My invention relates to card filing devices and more particularly to a protected file unit or box to contain a succession of data sheets or record cards, with means to enable 5 the selection of a desired card or data sheet with facility and dispatch, while preventing unauthorized tampering with the records or the removal of such sheets or cards.

In the present invention there is embodied 10 a box-like container, having a transparent normally locked lid or cover through which the data sheets or cards may be observed, the container having access openings therein through which a spatula or other suitable 15 instrument may be inserted for the purpose of turning the cards or separating the collection of cards into portions by oscillating them to and fro to expose any selected card. To facilitate the turning over or oscillation 20 of the cards within the container, the access openings for the spatula or implement are preferably located in a movable section in the present instance in a traveling belt, which passes over guide rollers at the corners of the lid, and is intermittently advanced by the pulling effort upon the inserted spatula or instrument, necessary to turn or separate the cards. In lieu of the 25 endless belt there may be employed a succession of short rollers arranged side by side with sufficient play or lost motion to permit the insertion of the separating spatula, between any two rollers, or such access 30 openings for the insertion of the card-turning implement may be made in a reciprocating bar, mounted in the side of the container. If it is desired that cards or data 35 sheets shall be placed in the file box or container, the transparent lid is provided with spaced transversely arranged slots, through 40 which additional cards or data sheets may be deposited between particular guides of the card or sheet collection within the box. If it is desired to lock the container against 45 such deposit of additional cards or data sheets, transverse stop bars or wires are provided which by relative movement of the slotted transparent top and such stop wires are brought into registry with the slot or 50 moved out of registry at the will of the operator. To prevent the deflection of a card or data sheet over or around such stop bar, the transverse rods or bars are preferably channelled. The relative adjustment 55 of the slotted transparent top and such stop rods or bars is controlled by a key-operated

lock. The object of the invention is to improve the structure as well as the operation of file boxes or containers whereby they will not only be cheapened in construction and 60 economical in manufacture, but will be easily and quickly operated to effect the selection of the desired card or data sheet, compact in form, adaptable to a wide range of 65 uses and unlikely to get out of repair. 65

A further primary object of the invention is to provide full and complete protection against the intentional abstraction or accidental loss of record cards or data sheets, or the alteration of records contained thereon by rendering the information or data sheets contained in the file box inaccessible for removal or alteration or destruction, yet 70 easily and quickly available for observation. 70

A further object of the invention is to provide improved protective means for a series of cards or data sheets, which while preventing removal or tampering therewith, will nevertheless enable the addition or insertion at selected points of additional cards 80 or data sheets and to further provide means for locking the file box or container against the insertion of such additional record sheets. 80

With the above primary and other incidental objects in view as will more fully appear in the specification, the invention consists of the features of construction, the parts and combinations thereof, and the mode of operation or their equivalents as 90 hereinafter described and set forth in the claims. 85

In the accompanying drawing, wherein is shown the preferred, but obviously not necessarily the only form of embodiment of the 95 invention, Fig. 1 is a perspective view of the assembled file box or container, showing the cards therein, and a file index mounted on top of the box or container. Fig. 2 is a longitudinal sectional view of the file box 100 or container, with a series of cards therein. Figs. 3 and 4 are detail perspective views of a slotted closure top in unlocked and locked positions. Fig. 5 is a bottom plan view partly broken away of a transparent 105 top or lid removed from the box or container. Fig. 6 is a sectional perspective view of the transparent closure lid, showing the relation of the endless traveling apertured belt. Fig. 7 is a detail perspective 110 view illustrating a modification wherein a series of independent rollers are employed.

in lieu of apertured belt. Fig. 8 is a side elevation of the lid or closure partly broken away, illustrating a reciprocatory bar having apertures therein to be employed in lieu 5 of the belt or rollers. Fig. 9 is a perspective view of the file box constructed of glass. Fig. 10 shows a modification of Fig. 9, with the box open. Fig. 11 is a detail view of the sheet-retaining means for the guide cards 10 and fixed data sheets between which cards may be loosely deposited. Fig. 12 is a detail view of the modification illustrated in Fig. 7.

Like parts are indicated by similar characters of reference throughout the several views.

Referring to the drawings, 1 is a box or container preferably, though not necessarily formed from sheet metal and having hollow walls 2, which afford stability. The box 20 1 is adapted to contain a series or collection of file cards, data sheets or other record cards 2. They are supported in inclined grouped relation by an adjustable follower 25 3, movable longitudinally by a screw shaft 4 in the bottom of the box, and operated by a revolute knob 5, projecting exteriorly thereof. At the forward portion of the box is provided a hinged plate or follower 6, 30 operated by a push rod or stem 6', to oscillate rearwardly such portion of cards 2 as may have been shifted forward to expose a selected card or data sheet. The container 1 is provided with a closure lid 7, which may 35 be hinged to the box 1 but which is normally locked to prevent access to the box or container, and tampering with the cards or data sheets therein. The box lid or cover is provided with a transparent panel 8, 40 through which the inscriptions upon the cards or data sheets 2 may be observed. In the event that it is intended that additional cards or data sheets shall be inserted or deposited within the box or container between 45 certain selected cards of the collection 2, the transparent panel 8 is composed of a series of spaced sections of transparent material preferably glass, leaving therebetween narrow slots or crevices 9. Such slots 9 are of 50 comparatively narrow width, only sufficient to admit the card or sheet to be deposited, but not wide enough to permit the insertion of any implement by which the deposited cards or sheets might be withdrawn. If 55 the file container is intended merely as a depository for records to which no additions are to be made by persons not having access to the container, the transparent observation panel 8 may be continuous throughout and 60 the depository slots 9 may be omitted. However, by providing for the deposit of such additional record cards through the slotted top, the file may be employed for stock accounting, directory purposes, or for 65 workmen's time records. In such applica-

tion, the guide cards of the file group 2 may indicate different classes of stock of which additions and deductions are indicated upon record cards deposited between the guides. Likewise the guides may indicate districts or 70 delivery routes and the deposited cards may comprise a directory of such districts or routes, to which additions may be made from time to time. When used as a paymaster's record, the guides may disclose the names or numbers assigned to different workmen whose daily time cards may be filed by being deposited through the slots. Whether 75 provided with the deposit slots or not, the file may be used for a series of protected ledger cards. In any event, the record upon any card or sheet may be observed through the transparent panel, upon separating the cards by the spatula inserted through the lateral access opening, and if desired additional cards or memoranda sheets may be deposited from time to time through the 80 slots in association with particular previously filed cards. To provide for the locking of such cover against the insertion or deposit of additional sheets or cards, the spaced transparent sections of the panel 8 are mounted in a suitable frame 10, which in turn is mounted for limited reciprocatory movement in a fore and aft direction, or 85 transverse to the direction of the slots 9, in the cover lid 7. The to and fro movement of this transparent framed panel is controlled by a key-operated lock 11, the ordinary lock bolt of which is connected to the panel 90 frame, so that the frame is shifted to and fro as the lock is manipulated. Fixedly secured transversely in the main frame of the closure lid or top 7, and in spaced relation corresponding with that of the deposit slots 9, 95 is a series of stop bars or wires 12. These stop bars or wires are preferably, though not necessarily, channelled, and are approximately of the size and shape of the ordinary umbrella rib of the present time. By the 100 to and fro shifting movement of the transparent panel 8, the deposit slots 9 thereof are moved into and out of registry with the stop wires or baffles 12. When such slot 9 is out of registry with the stop wire or baffle 12, the record card or data sheet may be 105 freely inserted as shown in Fig. 3. However, when adjusted to bring the slot 9 into registry with the stop wire or baffle 12, the slot will be closed, and the insertion of additional sheets or cards prevented, as shown in Fig. 4. The grooved character of the baffle wire or stop 12, causes the trapping or engagement of the edge of the sheet or card, which might otherwise be passed over or around the stop baffle, and into the container. 110

In the event that the file box or container is employed as a record file or to hold cards and sheets pertaining to personal trans- 115

120

125

130

actions, as stock and bond records, signature cards for banks, policy records or the like, the records within the container may be divided numerically or the divisions and 5 sub-divisions may embody both letters and numerals, in which event an alphabetical name index 13 is preferably though not necessarily mounted on top of the container or box. Such an index has been shown in Fig. 10 1, consisting of a series of name lists, subdivided and tabbed alphabetically. This collection of name lists or alphabetical index is mounted in a suitable carrier 14, detachably engaged beneath overhanging ledges 15 or flanges 15, projecting from the margins of the closure lid 7.

To enable the selection of any desired card, and separation of the collection or group of 20 record cards 2 into portions to expose the selected card by tilting a portion of such cards forwardly, the box or container 1 is provided in the side wall thereof, with a series of spaced apertures 16. A spatula or other thin-bladed instrument 17, may be introduced 25 through any one of the apertures 16, and by looking through the transparent panel 8 of the lid, the operator may guide such spatula or instrument 17 between any two adjacent cards. By movement of the spatula or selecting instrument 17, those cards in advance 30 of the point of separation may be tilted forwardly in the same manner that a card file is opened by manual manipulation when access is afforded direct to the cards. There 35 being a series of the apertures 16 which are located at spaced intervals, the operator selects the aperture most convenient to the point of operation or in other words, close to the card to be selected. The group or collection 40 of record cards may be separated at different points by inserting the implement 17 through different apertures 16, and then transmitting through such inserted implement 17, the motion necessary to tilt the advance 45 portion of the cards forwardly. These apertures 16 for the insertion of the selecting instrument 17 may be fixedly located in the side wall of the box or container. However, for convenience of operation, they are 50 movable in relation with the container, whereby instead of a prying or oscillatory movement of the implement 17 as is necessary to separate the records when the apertures are stationary, the entire implement 17 55 may be drawn forwardly and thus be made to follow the advance of the tilted or separated portions of the cards or record sheets. While several methods of enabling such shifting movement of the selecting implement 60 17, and the aperture 16, through which the implement is inserted, may be employed the preferred construction consists of an endless traveling belt 18, extending about guide rollers 26 located adjacent to the corners of 65 the closure lid 7 and in which the apertures

16 are formed. The lid 7 is provided at one side with a slot 19, with which the traveling belt 18 registers, and by which the slot is closed except for the apertures 16 in the traveling belt. The belt 18 may be of any suitable flexible material. It may be of thin metal, or of composition. However, in practice a leather belt 18 having the apertures 16 formed therein at intervals is found very satisfactory particularly in view of the fact 70 that it is noiseless in its movement. The implement 17 being inserted through an aperture 16 of the traveling belt 18, in close proximity to the card to be selected, and thence inserted between the selected card and the one in advance thereof, the implement 17 is bodily drawn forwardly as indicated by the arrow in Fig. 1, carrying with it not only the separated portion of the cards within the box or container, but also the traveling apertured belt 18. By employing an endless belt 75 passing entirely about the closure lid 7, it is not necessary to return the belt preparatory to the next selecting operation. After each operation, the endless belt 18 is left in its advanced position and upon the succeeding operation, the implement is inserted through another aperture and the belt again advanced. Thus the apertured belt 18 travels 80 through an intermittent step by step movement around the lid 7, being enclosed within the hollow or tubular margins of such closure lid. In Fig. 7 there is shown a modification, wherein in lieu of the endless traveling apertured belt 18, a series of independent 85 studs or rollers 20 are located side by side, in the channeled or tubular sides of the closure lid 7, to form a continuous series movable about the lid. The rollers are so proportioned that when closely assembled in their containing tube or channel, there will be slight play between the respective rollers or studs sufficient to permit the insertion through an opening in the sides of the channel 90 of the selecting implement 17 between any two adjacent rollers or studs 20. That is to say, the series of studs or rollers does not quite fill the track or circuit, so that sufficient play or lost motion is permitted to enable any two studs or rollers to be separated a sufficient distance to enable the insertion of the selecting implement 17. When this implement is inserted between adjacent 95 studs or rollers 20 and engaged with the selected cards within the box or container, it may be drawn forwardly thus advancing the entire series of rollers or studs 20 in quite the same manner that the endless belt 18 is advanced. 100

As a further modification of this construction, there has been shown in Fig. 8 a reciprocating bar 21, mounted for to and fro movement in the side frame of the closure lid 7 and having therein the apertures for the insertion of the selecting implement 17. 105 110 115 120 125 130

This bar 21 is normally retracted by a spring 22. The selecting implement 17 being inserted through any one of the apertures 16, the implement and with it the bar 21 may be drawn forwardly against the tension of the spring 22, to tilt the separated portion of the card group. Upon release of the reciprocatory bar 21, it will be retracted by the spring 22 preparatory to the next selection operation. The primary objection to the constructions shown in Figs. 7 and 8 is only the fact that they are somewhat more noisy than the endless belt construction shown in the preceding figures, and induce a clicking sound as the rollers are displaced one against the other, or as the reciprocatory bar 21 is returned by the retraction of the spring.

In Fig. 1 there have been shown additional apertures 23, located in proximity to the bottom of the box or container 1; through which the implement 17 may be inserted and by a prying or oscillatory movement employed to straighten or adjust the cards within the box or container, or to shift their lower bearing edges within the box to accommodate an adjustment of the follower block 3. Such additional apertures 23 are not ordinarily necessary nor essential but may be desirable under certain conditions of use.

In Figs. 9 and 10, there is shown a construction wherein the box or container is provided with transparent glass sides, as well as top. This enables the operator to more readily observe the filed cards in making a selection, and also admits light to enable the inscription or data to be more easily and quickly read. The cabinet or container as shown in Figs. 9 and 10 further differs from that shown in the preceding figures, in that the slotted transparent top and transparent side and end sections comprise the integral cover unit, which is pivoted or hinged to the bottom portion. By thus extending the lid or cover previously described to include the full height of the side and end section, the filed cards are more easily accessible when the lid or cover portion is raised as shown in Fig. 10. While a traveling apertured strap, an apertured reciprocatory bar, or relatively fixed spaced apertures in the side wall of the container as previously described may be employed in the construction shown in Figs. 9 and 10, the side wall of the box or container is shown provided with an elongated continuous slot 24, through which the spatula or instrument 17 may be inserted for the purpose of tilting the filed cards. The spatula 17 may be engaged with any selected card, and thence moved longitudinally in the slot 24, to tip the cards forwardly, and so open the file for observation. In lieu of the plunger stem 6' for returning the cards, the

forward follower 6 is drawn upwardly and rearwardly by a cord 25, attached at one end to the oscillatory follower 6 and at its opposite end to the spatula 17. This cord 25, not only prevents the spatula being misplaced, and keeps it readily at hand, but provides a convenient means by which the cards may be restored and the spatula inserted for a subsequent selection almost as a single motion. While holding the spatula preparatory to making the selection, a slight pull upon the cord 25 will restore the tilted cards. The cards in the file box illustrated in Fig. 1 may be restored in the same manner by providing the cord 25 passing through an opening 26 in the side of the container and used in lieu of the push rod or stem 6'.

In Fig. 9 the file cards are shown mounted in a removable file support within the cabinet or box. This support consists of a flanged base 27 to which front and rear followers 6 and 3' are hinged. The forward oscillation of the forward followers 6 is limited by stop arms 28. The stop arms 28 are pivoted to the hinged follower 6. A similar pair of stop arms 28 is also pivoted to the rearward hinged follower 3'. In Fig. 10 a single arm 28 is shown performing the same function as the pair of arms illustrated in Fig. 9. These arms are curved outwardly at their lower ends forming feet or props which engage the base of the cabinet or container to support the followers 6 and 3'. These stop arms normally hold the followers 6 and 3' in their elevated positions and limit their normal range of oscillation to positions inclined slightly forwardly and rearwardly respectively. However, by turning the stop arms 28 about their pivotal connections to transverse positions, the followers 6 and 3' may be lowered into horizontal positions, as indicated in dotted lines in Fig. 10. This movement of each follower is independent of the other. By lowering the followers 6 and 3', the series of file cards or sheets are opened in substantially book form, and to a flat position to facilitate writing upon the cards or sheets and making entries. The entire file and its support shown in Fig. 9 may be bodily removed from the file box or container.

In Fig. 10 there is shown a file support adjustable upon the base 29. The bottom or base 29 of the container is provided with longitudinally disposed upstanding flanges 30, upon which the bases 27' of the forward oscillatory follower 6 and the rearward follower 3' are slidably adjustable. Longitudinally disposed rods 31 extend in parallel relation intermediate the flanges 30 being supported in the base portions 27' of the respective followers, upon which the cards or leaves are engaged or strung in the usual manner by projecting the rods through cor-

responding perforations in the cards. The follower 6 is engaged with the flanges 30 at spaced intervals by a transverse rod or pin 32, engaging through registering holes 33, in 5 the upstanding flanges 30 and in ears 34, upon the follower base 27.

For locking the container or box in closed position, a narrow section 35 is hinged to the forward edge of the bottom or base 29, 10 and is provided with a lock 36, engageable with a corresponding metallic section 37, at the lower edge of the front end wall of the cabinet or box. The slotted top of the glass cabinet or box shown in Figs. 9 and 10, is 15 preferably provided with the guard baffles 12, by which the deposit slots may be closed as before described. These baffles or closure wires 12 are preferably controlled from a lock 11, in this instance, located adjacent to 20 the back end of the container top.

The glass panels forming the side and end walls of the container may be secured together in any suitable manner. In the present instance, there have been shown posts 39 25 located at each corner of the container having laterally disposed studs projecting through the adjacent panels and provided with nuts on their outer ends. At the rear end of the box, the posts 39 are hinged to 30 the rear end of the base 29, to provide for the pivotal movement of the container, to its elevated or opened position shown in Fig. 10.

It will be understood that the guide cards 35 and certain record or data cards of more or less permanent character may be attached to the file support by means of the longitudinal rods 31, shown in Fig. 10. Other record cards may be loosely deposited between such attached cards from time to 40 time. In Fig. 9 there is shown a somewhat different means for holding the guides and permanent records. This consists of a pair of interconnected rods 38 forming a clevis-like member. The interconnected rods 38 45 extend through the flanges of the base 27, and through perforations in the sheets intermediate such flanges. To retain the rods 38 against withdrawal, the rods are notched upon their adjacent faces and immediately 50 inside the forward flange of the base 27. A thin plate or slide 42 extending parallel with the forward flange of the base 27 is removably engaged in the alined notches 40 of the rods 38. The plate 42 is flanged outward at its top 55 margin to overhang the edge of the forward flange of the base 27. This outwardly extending flange 41 extends between the base flange and the hinged follower 6 when the latter is elevated. The follower, therefore, holds the plate in locking position. The plate can only be withdrawn by lowering the follower 6 out of the path of withdrawal of the plate 42.

60 Cross reference is made to co-pending application Serial No. 328,879, filed October 6, 1919, and the construction claimed therein of which the present construction is a further development and amplification.

Cross reference is made to Patent No. 1,639,016, issued Aug. 16, 1927 upon co-pending application Ser. No. 328,879, filed Oct. 6, 1919 and the construction claimed of which the present construction is a further development and amplification. Fur-

thermore the claims withdrawn herefrom on requirement for division and pertaining to closure means for the deposit slots 9 and closure means for the lateral access slot of the housing are not abandoned, but as at 80 present advised, will form the subject matter of a separate divisional application.

From the above description it will be apparent that there is thus provided a device of the character described possessing the 85 particular features of advantage before enumerated as desirable, but which obviously is susceptible of modification in its form, proportions, detail construction and arrangement of parts without departing from the 90 principle involved or sacrificing any of its advantages.

While in order to comply with the statute the invention has been described in language more or less specific as to structural features, 95 it is to be understood that the invention is not limited to the specific details shown, but that the means and construction herein disclosed comprises the preferred form of several modes of putting the invention into 100 effect and the invention is, therefore, claimed in any of its forms or modifications within the legitimate and valid scope of the appended claims.

Having thus described my invention, I 105 claim:

1. In a filing device, a container for a series of vertically positioned data sheets, a cover therefor, having therein a slot extending in parallel relation with the data 110 sheets, means for effecting the separation of the series of sheets in proximity to said slot to permit the deposit of an additional data sheet through said slot in predetermined relation with previously filed data sheets. 115

2. In a filing device, a normally locked container for a series of data sheets, having therein a deposit slot through which sheets may be inserted into the container, means for effecting the separation of the series of 120 data sheets, within the container at selected intervals for the insertion of additional data sheets therebetween through said slot in predetermined relation with previously filed sheets. 125

3. In a filing device, a normally locked container for a series of data sheets, an observation window in the container through which the sheets may be observed without affording access thereto for removal or 130

tampering, means for effecting the separation of the series of sheets to expose a selected sheet, said container having therein an opening for the deposit of additional data sheets in association with an exposed sheet.

4. In a filing device, a normally locked container for a series of data sheets, the container having therein a plurality of spaced slots extending in substantially parallel relation with the enclosed data sheets through which additional data sheets may be introduced into the container, and means for effecting the separation of the enclosed data sheets at points in proximity to said slots whereby the additional sheets introduced through such slots may be deposited between the separated portions of the previously filed data sheets.

10 5. In a filing device, a container for a series of substantially vertically disposed data sheets, a slotted cover for the container through which additional sheets may be deposited in the container, said container having an access opening in the side thereof through which the sheets may be manipulated to enable the exposure of a selected sheet and to permit the deposit of additional sheets between selected sheets within the

20 30 container.

6. In a protected filing device for loose sheets, a container, a slotted cover panel through which sheets may be inserted into the container and an access opening through which the sheets within the container may be separated to enable the deposit of additional sheets at predetermined intervals.

7. In a protected file device for data sheets, a container having in one wall thereof slots for the deposit of additional sheets into the container, and also having in another wall thereof an aperture through which an implement may be inserted in substantially parallel relation with the sheets and by which the sheets may be separated at selected points to admit of other sheets being deposited through said slots.

8. In a protected file, a container for a plurality of data sheets, having a transparent closure through which the sheets within the container may be observed, and having an aperture in a vertical side wall of the container through which an implement may be inserted in substantially parallel relation with the data sheets and by which the sheets may be separated within the container to permit observation thereof.

9. In a protected file, a container for a succession of data sheets, a transparent top panel for the container through which the data sheets may be observed, and an apertured side panel for the container through which an implement may be inserted into the container for the purpose of separating the sheets for observation, but

not permitting the removal of the sheets from the container.

10. In a protected file device, a container for a succession of data sheets, a transparent top panel for the container through which the contents of the container may be observed, said container having an elongated slot in the side thereof, for the insertion of an implement into engagement with the data sheets, and movement of the same longitudinally of the slot for the purpose of separating selected portions of the sheets.

11. In a protected file box, a housing for a series of data sheets including a transparent panel through which the data sheets may be observed, said housing having a slot in a wall thereof extending transversely in relation to the planes of the sheets through which the data sheets may be manipulated to expose a selected sheet to view.

12. In a protected file box, a housing for a series of data sheets including a transparent panel through which the data sheets may be observed, the housing having an access opening in a vertical side wall thereof through which access may be had for separating the sheets to expose to view a selected sheet.

13. In a protected file box, a housing for a series of data sheets including a transparent panel through which the data sheets may be observed, said housing having an access slot therein for the introduction of an implement into engagement with the data sheets and movement of the same longitudinally of the slot for separating the sheets to expose to view a selected data sheet.

14. In a protected file for a series of data sheets, a housing having a transparent panel through which the data sheets may be observed and an opening, means operable from the exterior of the housing through said opening for separating the data sheets for observation, a follower member for said data sheets, and a pull cord attached to the follower, for returning the separated data sheets preparatory to the next selective operation.

15. In a protected file for a series of data sheets, a housing having a transparent panel through which the data sheets may be observed and an opening, means operable from the exterior of the housing through said opening for separating the data sheets for observation, a follower member for said data sheets, and a pull cord attached to the follower, connected to the data sheet separating means whereby the movement of the separating means in reverse direction will operate the follower to restore the data sheets preparatory to the next selective operation.

16. In a protected file, for a series of data sheets, a housing having a transparent panel through which the data sheets may be observed and an opening, and selective means

- operable from the exterior of the housing through said opening for separating the sheets for observation by its movement in one direction and operative upon reverse movement to automatically restore the separated sheets.
17. In a protected file for a series of data sheets, a housing having a transparent panel through which the sheets may be observed and an opening, a movable follower for the data sheets by the movement of which the sheets may be restored preparatory to the next operation, and a selective member having permanent operative engagement with the follower by which its movement in one direction will operate the follower to restore the data sheets, said selective member capable of insertion through said opening for engagement with different data sheets to separate the series of sheets for observation by its movement in the opposite direction.
18. In a protected file for a series of data sheets a housing having a transparent panel through which the sheets may be observed and an opening, a movable follower for the data sheets by the movement of which the sheets may be restored preparatory to the next operation, a selective member for insertion through said opening for separating the data sheets for observation, and a pull cord connecting the selective member and the follower.
19. In a protective file for a series of data sheets, a housing having a transparent top, through which the data sheets may be observed and an opening, and means operable from the exterior of the housing through said opening for separating the data sheets for observation and restoring the sheets preparatory to the next operation.
20. In a protected file for a series of data sheets, a housing provided with an opening in combination with means operable from the exterior of the housing through said opening for separating the series of sheets for observation and for restoring the separated sheets, said data sheets being observable through the top of such housing.
21. In a protected file a series of data sheets, a housing comprising transparent top, side and end walls, and a bottom section in relation with which the housing unit comprising the top side and end walls is relatively movable.
22. In a protected file for a series of data sheets, a bottom section, means upon the bottom section for supporting a series of data sheets, and a unitary enclosure for said data sheets comprising top, side and end walls, said unitary enclosure being engageable with and disengageable from the bottom section to afford access to the data sheets.
23. In a protected file, for a series of data sheets, a bottom section, means upon the bottom section for supporting a series of data sheets comprising top, side and end walls, hinged to said bottom section and relatively movable in relation thereto to and from closed position.
24. In a file for a series of data sheets, a container, a follower mounted for oscillatory movement within the container, and a stop member normally limiting the range of oscillation of the follower to maintain the data sheets in an approximately upright position, said stop being retractile to permit the follower to be oscillated to an extreme position to enable the data sheets to be adjusted to a recumbent position.
25. In a file for a series of data sheets, a container, a follower mounted for oscillatory movement within the container, limiting means for normally confining the follower to a restricted range of oscillation by which the data sheets are maintained in an approximately upright position, said follower being capable of further movement to a recumbent position in which the data sheets will be presented in convenient position for writing thereon, when released from such limiting means.
26. In a file for a series of data sheets, a container, a follower mounted for oscillatory movement within the container, and a prop arm pivoted to the follower and normally limiting the oscillation thereof, said prop arm when oscillated about its pivotal connection permitting the follower to be oscillated to an extreme degree permitting the data sheets to be positioned for writing thereon.
27. In a protected file for a series of data sheets, a closed housing within which the data sheets are visible for observation, means operable from the exterior of the housing for separating the sheets for observation, and a unitary mounting for the data sheets, removable with said data sheets from the housing.
28. In a protected file for a series of data sheets, a closed housing within which the data sheets are visible for observation, means operable from the exterior of the housing for separating the sheets for observation, and an independent mounting within which the data sheets are connected, said independent mounting being insertable within and removable from the housing without detachment of the sheets.
29. In a file for a series of data sheets, a mounting for the data sheets including an oscillatory follower, a retainer rod transfixing the series of sheets and a locking member for said rod in the path of disengagement of which the oscillatory follower normally extends to prevent the disengagement of the locking member until the follower is oscillated to an abnormal position.

30. In a file for a series of data sheets, a mounting for the data sheets including an oscillatory follower, a retaining rod transfixing the data sheets, and locking means controlled by the oscillatory follower and permitting the disengagement of the rod only when the follower is oscillated to an abnormal position.
31. In a filing device, a series of oscillatory file members, an enclosure therefor, preventing access thereto for removal or disarrangement, but permitting observation thereof, said enclosure having therein an access opening through which any one of the members of the series may be selected from the exterior of the enclosure by an implement inserted through said access opening, the series of file members being separated to expose the selected member to view by the relative movement of a portion of said file members and the implement one to the other.

In testimony whereof I have hereunto set my hand this 24th day of January, A. D. 1924.

RODNEY J. WOOD.
